WILLIAM RIEKIE WATSON, OF STOCKTON CALIFORNIA.

Letters Patent No. 87,384, dated March 2, 1869.

IMPROVEMENT IN HORSE-SHOES.

The Schedule referred to in these Letters Patent and making part of the same.

To all whom it may concern:

Be it known that I, WILLIAM RIEKIE WATSON, of Stockton, county of San Joaquin, State of California, have invented an Improved Horse-Shoe; and I do hereby declare the following description and accompanying drawings are sufficient to enable any person skilled in the art or science to which it most nearly appertains, to make and use my said invention or improvements without further invention or experiment.

The object of my invention is to provide an improved shoe for horses, so constructed that the horse's heel is freely permitted to expand, as well as making a much easier and useful shoe for the horse.

It is well known that the usefulness of the horse depends, to a great degree, on the endurance and strength of his foot, being composed, as it is, of numerous small bones, nicely arranged and adjusted, so that when they are in a healthy condition, they are capable of exerting great strength, and with great endurance. This part of a horse's foot should be allowed to expand freely, each part occupying its intended position, and, when from any cause this expansion is checked, the consequence is, that the foot becomes diseased, and the horse will be crippled in his feet, so that his value is greatly impaired. This is especially the case when horses are shod when young, and allowed to retain the shoes a great length of time without changing.

To avoid this difficulty, I construct my shoe in three different parts, separating the two heel-pieces from the toe-piece, by means of V-shaped joints. These joints are bevelled, the toe resting on the bevel of the heel-pieces, thus giving the heel a chance to expand either way.

To more fully illustrate and explain my invention, reference is had to the accompanying drawings, forming part of this specification; of which—

Figure 1 is a plan view of my improved shoe. Figure 2 is a side view of the shoe, seen edgewise. A is a section of a horse-shoe, forming the toe, and B and B', the heel-pieces.

These sections are secured to the horse's hoof, by means of nails, in the usual way, each section being placed on the portion of the hoof where it properly belongs. The heel-pieces B B' are the first to be nailed to the hoof, as the end a, pointing towards the toe, is pointed and bevelled on the upper side, as shown. The two ends of the toe-piece are cut out in the shape of a V, and bevelled on the lower side. The toe-piece is placed on the hoof, so that the bevel of the V-shaped cut will rest upon the bevel of the heel-pieces. By this management, I save the liability of breaking the nails in the heel-pieces, and give more freedom of action to the toe, while the heel of the horse is permitted to expand in either direction freely. The shoe need not be in other particulars different from those now in use. The nails, in number and place, will depend on the condition of the hoof, which, if sound, will require but six. Eight nails are commonly used for the old-style shoe, seldom seven, and six very unusual.

Having thus described my invention,

What I claim, and desire to secure by Letters Patent, is—

The above-described shoe for horses, consisting of a toe-piece and two heel-pieces, adapted to fit together, but to be nailed on separately, substantially as described.

In witness whereof, I have hereunto set my hand and seal.

WILLIAM RIEKIE WATSON. [L. S.]
